[57] **CLAIM**

The ornamental design for a fastener driving device housing, as shown and described.

DESCRIPTION

FIG. 1 is a perspective view of a fastener device housing showing my new design, looking at the top, from the left side, the magazine assembly and the nosepiece of the device being shown in phantom lines;

FIG. 2 is a top plan view thereof;

FIG. 3 is a bottom plan view thereof;

FIG. 4 is a left side elevational view thereof, the right side thereof being a mirror image thereof;

FIG. 5 is a front elevational view thereof; and,

FIG. 6 is a rear elevational view thereof.

The broken line showing of the magazine assembly and the nosepiece is for illustrative purposes only and forms no part of the claimed design.
